UNITED STATES PATENT OFFICE.

VICTOR VON ALPENBURG AND LOUISE VON ALPENBURG, OF WEST HOBOKEN, NEW JERSEY.

SKIN-PRESERVING COVERING.

No. 891,653.

Specification of Letters Patent.

Patented June 23, 1908.

Application filed December 7, 1907. Serial No. 405,571.

To all whom it may concern:

Be it known that we, VICTOR VON ALPENBURG and LOUISE VON ALPENBURG, citizens of the United States, residing in West Hoboken, in the county of Hudson and State of New Jersey, have invented certain new and useful Improvements in Skin-Preserving Coverings, of which the following is a specification.

10 This invention relates to an improved covering for preserving and improving the condition of the skin of the face, neck, hands and other exposed parts, and to heal injuries to the same, remove wrinkles and restore the 15 skin to an improved and healthy condition; and for this purpose the invention consists of a skin-preserving device which comprises three layers, an interior layer formed of the core of a Chinese palm-tree, and an intermediate layer of the same material which is 20 impregnated with a medicinal substance for restoring and preserving the skin of the exposed parts of the body, and an exterior reinforcing layer of a textile fabric.

25 In the accompanying drawings, Figure 1 represents a front-view of a skin-preserving covering made according to our invention in the nature of a face-covering or mask, Fig. 2 is a front-view of the covering in the shape of 30 a half-mask, and Fig. 3 is a horizontal section on line 3, 3, Fig. 1.

Similar letters of reference indicate corresponding parts.

In making our improved device for preserving and treating the skin of the exposed parts of the body, such as the face, neck and the hands, we employ thin layers that are obtained from a Chinese palm known by the botanical name of *Aralia papyrifera*, a material which is also used extensively in the manufacture of artificial flowers. These layers are carefully treated before use by first subjecting them to the hot vapors of alcohol and then rendering them pliable by a 45 glycerin-solution.

Our skin-preserving device consists of a thin continuous interior layer *a* of the palm-core, an exterior layer *d* of a textile fabric, preferably silk, and a thin intermediate 50 layer *b* of the palm-core which is treated with a medicament desired for preserving the skin.

The intermediate layer *b* may be made of smaller pieces, such as are obtained in the manufacture of artificial flowers from the *Aralia papyrifera*. The exterior layer *d* of 55 textile fabric serves for reinforcing the intermediate and interior layers *a* and *b* as they have not sufficient strength for resisting the strain on the same. The skin-preserving layer may be made in the form of a mask or 60 half-mask when used for the face, or in the shape of a bandage, when used for the forehead, neck or hands, the exterior reinforcing layer *d* permitting the attachment of bands or other fastening devices to the mask band- 65 age or other covering.

When the covering is applied to the exposed parts of the skin, such as the upper part of the face, neck, hands etc., the skin-preserving or restoring substance with which 70 the intermediate layer is saturated, is transmitted through the pores of the interior layer *a* to the skin in the quantity required. The interior layer is soft and pleasant to the skin and possesses almost the same degree of 75 flexibility as the natural skin, so that the covering is not disagreeable and objectionable when placed on the part to be treated. The covering can be applied for various sanitary, healing and hygienic purposes; also in smaller 80 pieces, in the nature of plasters, for the healing of sores and wounds by varying the medicament with which the intermediate layer is impregnated. As the layers of palm-core are treated with a solution of glycerin they 85 retain their softness and pliability for a considerable length of time, so that the covering can be used at any time without getting stiff, brittle and objectionable to the skin.

The advantages of our improved skin-preserving covering are that the skin is restored to its natural healthy condition, that face-wrinkles can be removed or softened to a great extent, and that sore or injured parts of the skin can be healed in a quick and effective manner.

Having thus described our invention, we claim as new and desire to secure by Letters Patent:

1. A skin-preserving covering consisting 100 of three layers, an inner prepared layer of palm-core, an intermediate layer of the same

material saturated by a suitable medicament and an outer layer of a textile fabric.

2. A skin-preserving covering consisting of an inner prepared layer of the core of the 5 *Aralia papyrifera*, an intermediate layer of the same material impregnated with a skin-preserving medicinal preparation, and an outer layer of silk.

In testimony that we claim the foregoing 10 as our invention, we have signed our names in presence of two subscribing witnesses.

VICTOR VON ALPENBURG.
LOUISE VON ALPENBURG.
